UNITED STATES PATENT OFFICE

HENRY J. SCHNEIDER, OF BOSTON, MASSACHUSETTS

WATER HEATER AND CONDENSER

Application filed May 11, 1929. Serial No. 362,437.

My present invention relates to water heaters and condensers and more particularly to a combined water heater and steam condenser.

5 My device is twofold. It not only condenses steam but the steam produces hot water, or in other words, heat which is present in the steam is transferred to the water, thereby chilling the steam to a condensation point 10 and raising the temperature of the water to a substantially high point, or sufficiently high enough for the requirements of a laundry, for instance.

Of course my apparatus might be used directly as a hot water heater being attached to a common steam heater, such that steam would be continually condensing in the water heater and returning to the boiler in the form of water, much the same as condensation takes 20 place in a steam radiator, except that in my invention the heat would pass from the steam to the water surrounding the steam coils instead of the atmosphere around a radiator.

In my device the cold water enters the bottom of the condenser and flows out of the top while the live steam enters the top of the condenser, and the condensed steam, in the form of water, flows out at the bottom. The steam is conducted through a series of coils supported in standard fittings, such as cast iron L's, T's, return bends and the like, and any size condenser or heater may be made by adding to or subtracting from the number of units without discarding any of the original equipment, and likewise the apparatus may be easily disassembled for cleaning or repairing without discarding or removing the rest of the apparatus.

The principal object of my invention therefore, is a combined water heater and condenser.

Another object is a water heater and condenser composed of a series of similar units any one of which is demountable without disturbing the others;

Other objects and novel features will appear as the description of the operation and construction of the device progresses.

In the drawings illustrating my preferred embodiment of the invention,

Fig. 1 is a side elevation of the water heater and condenser attached to the exhaust pipe of a steam engine;

Fig. 2 is an enlarged end elevation of the water heater shown in Fig. 1;

Fig. 3 is a transverse section taken on the line 3—3 of Fig. 1, and corresponding in size to Fig. 2;

Fig. 4 is a still further enlarged end elevation of one of the units with the steam inlet and outlet pipes removed, and

Fig. 5 is a section taken on the line 5—5 of Fig. 4 showing the special construction of the end cover plate;

Fig. 6 is another end elevation similar to Fig. 2 having the steam line connected in parallel instead of series.

Referring to the drawings, and particularly to Fig. 1, 10 indicates a stationary steam engine provided with an exhaust pipe 11 directly connecting such engine 10 with the water heater and steam condenser 12.

The water heater and steam condenser 12 may be composed of any number of units, and for purposes of illustration, I have shown six such units in A, B, C, D, E and F, each of which is composed of several standard fittings. These units are identical in every respect except the angle at which they may be set, and for this reason a detailed description of the first unit A will suffice for all.

A flanged pipe 13 is fitted at its front end with a flanged T 14, the offset opening 15, becoming the outlet for hot water. On the extreme front flange 16 of the T 14, (see Figs. 4 and 5) is mounted a disk 17 which has mounted therein a series of steam tubes 18, each tube being in the form of a long return bend, the bend proper 19, being positioned at the extreme end of the pipe 13 and suspended therein by the disk 17. Adjacent the front side of disk 17 is a cover plate 20, provided with an upper and lower chamber 21 and 22 respectively. A steam inlet opening 23 is provided in the upper portion of the plate 20, and directly connects with the chamber 21, connection to inlet opening 23 being made from the engine 10 by means of the exhaust pipe 11. Steam passes through the tube 18 and out of the lower

chamber 22 by way of the opening 24, and thence into a pipe 25, connecting the lower end of the tube 18 in unit A with the upper end of tube 18 in unit B, thence in the same manner via pipe 26 to unit C, and so on down to the outlet pipe 27 at which point the steam is condensed into water. Cold water enters the T 28 at the bottom, passing along the pipe 29, around the L's 30, at the rear and back, through the pipe 31, and thence up through the T's 32 and 33 into the unit D, and so on up through units C, B, and A, and out through the T 34.

The cold water circulates up through the jacket composed of standard fittings, absorbing the heat from the steam and may be drawn off the top for either domestic or commercial purposes. The steam may be either the exhaust of a steam engine or live steam from a steam boiler, such as is used for heating dwelling houses. In either event, steam is utilized to heat the water and the heat having been transferred from the steam to the water, the condensation of the steam is carried back to the boiler for further use.

In some installations, the units A, B, C, D and E, may take the place of a radiator for heating a room, while at the same time furnishing hot water for other purposes, and under such conditions, a combination of steam and hot water is present, the steam coils acting as an indirect heating unit for the hot water radiator.

At Fig. 6, I have shown a similar arrangement of the units A, B, C, D, E and F, except that the said units are provided with parallel steam coils such that steam travels down through the units A, D and E, without passing units B, C and F, and vice versa.

In some installations an arrangement of this character would be more desirable than that shown in Figs. 2 and 3, as it allows closer spacing of the units with respect to their vertical heights because no necessity is present for tipping the units for the purpose of drainage of the coils 18 through the pipes 25 as in the case in Figs. 2 and 3.

A common inlet T 35 connects with both sides as A, D, E, and B, C, F, and a common outlet T 36 receives the condensation the same as does the pipe 27 in Fig. 2 and in all other respects the units are identical with those shown and described elsewhere in the specification.

Having thus described my invention, what I claim as new is:

1. In a water heater, a plurality of demountable water jackets connected to each other at one end by a return bend and at the other end by a T, said T closed at one end by a disk provided with a steam tube having its two ends secured in said disk and communicating with the side of the disk remote from said water jacket, a cover plate adjacent said remote side of said disk and held to said

jacket by means of bolts passing through said cover plate, and disk and secured to said jacket, steam inlet and outlet openings in said cover plate communicating with chambers formed on the inside of such plate adjacent the said disk, a partition separating said compartments and transversely located between the open ends of said steam tube located in said disk, substantially as shown and described.

2. In a combined water heater and steam condenser the combination of demountable water jackets connected to each other at one end by a return bend and at the other end by a T, said T closed at one end by a disk provided with a steam tube having its two ends secured in said disk and communicating with the side of the disk remote from said water jacket, a cover plate adjacent said remote side of said disk and held to said jacket by means of bolts passing through said cover plate and disk and secured to said jacket, steam inlet and outlet openings in said cover plate communicating with chambers formed on the inside of such plate, adjacent the said disk, a partition separating said compartments and transversely located between the open ends of said steam tube, located in said disk, substantially as shown and described.

In witness whereof, I hereby subscribe my name this 18th day of March, 1929.

HENRY J. SCHNEIDER.
